United States Patent

Des. 236,136
Patented July 29, 1975

236,136

TELEVISION ANTENNA

Benjamin L. Snyder, Bala Cynwyd, Pa., assignor to
Snyder Manufacturing Company, Philadelphia, Pa.

Filed Aug. 15, 1973, Ser. No. 388,647

Term of patent 14 years

Int. Cl. D14—03

U.S. Cl. D26—14 F

FIG. 4

FIG. 1.

FIG. 2.

FIG. 3.

FIG. 5.

FIG. 1 is a front elevation of a television antenna, showing my new design;

FIG. 2 is a side elevation thereof;

FIG. 3 is a rear elevation thereof;

FIG. 4 is a top plan view thereof; and

FIG. 5 is a bottom plan view thereof.

I claim:

The ornamental design for a television antenna, substantially as shown and described.
